UNITED STATES PATENT OFFICE

2,447,916

BUILDING WALL

John W. Staggers, Washington, D. C.

Application February 11, 1944, Serial No. 521,983

3 Claims. (Cl. 72—107)

2

This invention relates to a building wall and aims to provide means whereby precast panels, sections, or slabs of water-proof concrete using Portland cement or the like, will be joined in a water or moisture-tight manner. It is aimed to provide a structure wherein the joints between the sections or parts of water-proof monolithic material comprises interfitting parts with opposed walls thereof having undercut grooves filled with water-proof cement as a binder and water-proofing agent, and which sets when the parts are in pressed or clamped relation one with respect to the other. It is also aimed to provide a structure wherein one part of the joint has a groove which receives the other part and advantageously receives the sealing cement for pressure dispersion in place. Further, it is aimed to provide a structure wherein the rib which enters the groove is reduced at its base to facilitate the entry of the rib and dispersion of the sealing cement against danger of trapping air.

The more specific objects and advantages will become apparent from a consideration of the description following taken in connection with accompanying drawings illustrating an operative embodiment.

In said drawings:

Figure 1 is an elevation, partly broken away, of a precast concrete slab or wall section using water-proof cement in its manufacture, and embodying the principles of the invention;

Figure 2 is a horizontal section illustrating the joint between a plurality of the parts of Figure 1;

Figure 3 is a horizontal sectional view showing portions of sections constructed according to Figure 1 but in spaced relation to disclose details;

Figure 4 is a side elevation of a modified form of the precast slab or wall section;

Figure 5 is a horizontal section showing the joint between sections of type disclosed in Figure 4;

Figure 6 is a horizontal section of the parts at the joint mentioned with respect to Figure 5, in spaced relation to disclose details;

Figure 7 is a perspective view, fragmentary, of one edge at the joint of a slab or section according to Figure 4;

Figure 8 is a perspective view of a modified form of key which may be used at the joint;

Figure 9 is a horizontal section corresponding to Figure 5 through a further modified form; and

Figure 10 is a vertical sectional view taken on the line 10—10 of Figure 9.

Referring specifically to the drawings wherein like reference characters designate like or similar parts, and first to the form of Figures 1 to 3, I use for the requisite construction of the wall, panels or sections 10 of any appropriate number and size. These sections are made of concrete utilizing a water-proof Portland cement or equivalent cement, so that when set and hardened, they will be water and moisture-proof. 10 Along one edge of the panel or section 10, I provide a rib 11 and along the parallel edge thereof, a groove 12 is formed so that the rib 11 will enter through groove 12 of adjacent slab or section as shown at the left in Figure 2. 15 It is to be noted that groove 12 is widened at the base to provide auxiliary undercut grooves 13, preferably semi-circular in cross section, and that in the adjacent side surfaces of the rib 11, corresponding grooves 14 are formed. 20 Before entering the rib into the groove 12, the latter has deposited therein, a water-proof cement from a predetermined quantity so that when the rib 12 is inserted, it will spread or disperse such water-proof cement to form sealing bodies at 15. Attention is called to the fact that the cement 15 is a water-proof Portland or equivalent cement and that the term is to be interpreted as covering a plastic mixture of the cement alone or with the sand or other ingredients incorporated therein. 25 The corners of the rib 11 are reduced or cut away as at 16, so that the rib 11 will more readily enter and disperse the plastic sealing material in its path, and reduce the danger of the trapping of air. 30 Particular attention is called to the fact that the slabs or sections 10 are joined when pressed one against the other by any suitable means and that such pressure may be applied by clamps and bracing, and temporarily secured to the sections, the same being permitted to remain on the sections until the sealing cement at 15 is set or hard. It will be realized that the bodies at 15 are of a water and moisture-proof nature and form an 35 intimate bond with the adjacent surfaces in the grooves 13 and 14.

A modified form of the invention is shown in Figures 4 to 7. Here, the slab or wall section is designated 10a and made from the same material as the sections 10 and at the joint between sections, I use a key section made of the same materials as sections 10 and 10a. Section 10a is constructed similarly along parallel sides. Such sides have projecting ribs 18 and at the junction of the ribs with the remainder of the side

wall surfaces, grooves 19 are provided. The key 17, adjacent one edge has recesses at 20 and such edge is reduced in width by slightly cutting away corners 21.

It will be seen that when the parts are assembled as in Figure 5, adjacent projections 18 of slabs or sections 10a abut and a groove is provided adjacent thereto into which the key 17 is pressed. Prior to pressing the key into position, the groove has a predetermined quantity of water-proof cement deposited therein in order that pressure of the key 17 against the same will disperse it and cause it to fill the grooves 19 and 20, thus keying the slabs or sections 10a and key 17 together, forming a water-proof joint, and binding or keying with all surfaces which it contacts. Attention is called to the fact that the parts are thus assembled with pressure applied to all of them, that is, the sections 10a and key 17, which pressure may be supplied in any suitable manner, as by means of clamps which clamp the sections 10a together and which clamp the key in contact with the projections 18.

A modified form of key 17 is shown at 17a in Figure 8. Instead of having the recesses 20, this key has projections 22 which are adapted to occupy the groove 19 and the space between sections 10a and projections 18 are in contact. Under such conditions, the side surfaces of key 17a and the surfaces of projections 22 are coated with sealing cement like that used at 15 so that all contacting surfaces of the key 17a and slab 10a will be sealed water and moisture-tight and will bind or bond with each other. It is clear that the key 17a is made of water-proof cement like the key 17.

A final modification is disclosed in Figure 10 wherein the wall or slab sections 10b are joined with a key section 17b disposed between them, all being made of the same material as the sections 10 and 10a. Such sections 10b and 17b are initially separate and it will be noted that in their engaging surfaces they have registering arcuate grooves at 22 and 23, the grooves 23 preferably being shallower than those at 22. The grooves are filled with a sealing cement 24 which binds or bonds with all contacting surfaces in addition to forming a water and moisture-proof joint. Cement 24 is the same as that used at 15.

It is to be understood that in a joint utilizing the key 17a of Figure 8 and the parts of Figures 9 and 10, that is, all joints, all of the parts entering into the same are united and maintained under pressure by means of clamps or in any other suitable manner, with the pressure maintained as long as desired and usually until the plastic or water-proofing cement has set or hardens.

Various changes may be resorted to provided they fall within the spirit and scope of the invention.

I claim as my invention:

1. In a wall construction, a joint, said joint being composed of a pair of connectable elements, one formed with a groove and the other with an interfitting rib, the grooved element being formed

with opposed undercut channels at the inner end of its groove, said rib being formed with channels at its free end, a cement deposit for the groove, the opposed channels of the elements being located to receive portions of the cement when the rib is forced into the groove and the cement is dispersed thereby, the outer side wall portions of the channels of the rib being shorter than the opposed sidewall portions to define the free end of the rib as of less cross-sectional area than the portion inwardly of the channels.

2. A joint construction comprising a pair of interfitting elements, one having a groove and the other a rib fitting in said groove, said grooved element being formed with an undercut channel at the innermost portion thereof and adjacent one side of the rib, said rib being formed with a channel at its outermost portion and in opposed relation to the channel of the grooved element, a cement deposit for the groove, the opposed channels of the elements being located to receive portions of the cement when the rib is forced into the groove and the cement is dispersed thereby, the outermost portion of the rib being reduced to permit passage of the cement around that portion of the rib as the rib is forced into the grooved element.

3. A joint construction comprising companion elements, one element being formed with a groove having side walls and an inner end wall and being of an even width for the major portion of its depth but having its inner end portion widened to form channels along the junction of its side walls with its inner end wall, the other one of said elements being formed with a rib fitting snugly into said groove and having side walls and an end wall, said rib being formed with side channels along the junction of its side walls and its end wall registering with the channels of the groove when the rib is inserted therein, and cement deposited in the inner end portion of said groove and forced into the channels of the groove and the tongue as the tongue is fitted into the groove.
